WRINGER

Charles W. Williams, Kinsman, Ohio

Application February 8, 1935, Serial No. 5,607

20 Claims. (Cl. 68—248)

This invention relates to a wringer, and especially to a household laundry wringer which utilizes rotating pressure rolls to squeeze water from the clothes. The general object of the present invention is to provide a power-driven wringer, of the rotary pressure roll type, which will prevent injury to the operator, and which will enable the operator to straighten the clothes and the buttons thereon, while the material is being fed to the wringer, without fear of injury.

Another object of this invention is to provide a wringer construction in which the power connection to the wringer rolls will be automatically broken and the rotation of the rolls stopped should the operator's fingers be inadvertently caught in the wringer mechanism.

I prefer to accomplish the above objects by providing a wringer with a pair of pressure rolls which coact to squeeze the water from the clothes, together with a supplemental or feeding roll arranged to coact with one of the pressure rolls in such a manner that clothes may be fed by the operator to the bite of said supplemental roll and its coacting pressure roll, and I so arrange the supplemental roll that it is resiliently urged toward the coacting pressure roll with a comparatively light degree of pressure, such pressure being insufficient to cause injury, should the operator's fingers be caught between the supplemental roll and its coacting pressure roll, and being so light that the operator may readily withdraw her fingers in case of such inadvertent gripping of the fingers by the supplemental roll and a pressure roll, and I so arrange the supplemental roll that, consequent upon undue amount of separation between it and its coacting pressure roll, the power connection between the driving mechanism and the pressure rolls will be automatically broken. This, therefore, is a more specific object of the invention.

Further objects of the invention will become more apparent from the following description, reference being had to the accompanying drawings, which illustrate a preferred form of the invention. The essential characteristics of the invention will be set forth in the claims.

In the drawings, Fig. 1 is a horizontal section of a wringer embodying my invention, the plane of the section being indicated by the line 1—1 on Fig. 2; Figs. 2 and 3 are vertical transverse sections through the wringer mechanism, as indicated by the line 2—2 and 3—3 on Figs. 1 and 4; Fig. 4 is a vertical longitudinal section, the plane of the section being indicated by the offset lines 4—4 on Fig. 1; Figs. 5 and 6 are vertical trans-

verse sections as indicated by the correspondingly numbered lines on Fig. 4; Fig. 7 is a sectional view similar to Fig. 4, but illustrating a modified form of my invention; Figs. 8 and 9 are sectional details, the planes of the sections being indicated by the correspondingly numbered lines on Fig. 7.

Referring now to the drawings, wherein I have illustrated a preferred form of my invention, it will be seen that I provide a wringer mechanism 10 having a pair of pressure rolls mounted in the same horizontal plane, beneath which are positioned a pair of supplemental rolls arranged in contact with respective pressure rolls.

The frame of the wringer, as shown in the drawings, comprises a box-like formation having an open top which is normally closed by a suitable cover 21, pivoted as at 22 to the frame. Material is fed to the wringer through openings 23 in either the front or rear wall of the frame 20 member and is ejected by the wringer rolls, as will hereinafter be described, through a suitable opening 24 in the top wall of the cover. The arrangement is such that materials may be fed from either of two opposite vertical faces of the wringer and guided upwardly between a pair of horizontally mounted pressure rolls 10 and 11, which coact to squeeze the water from the clothes and eject them from the top of the wringer.

As shown, the pressure rolls 10 and 11 comprise the usual rubber wringer rolls rigidly mounted on respective shafts 12 and 13, one of which shafts, for instance the shaft 13, is carried in suitable bearings 14, which are secured to the cover 21 by bolts 15. The other wringer roll shaft 12 is mounted in bearing members 16. The bearing members 16 are each provided with a stud 17, which is slidably carried in respective yokes 18 pivoted at 19 to the frame 20 of the wringer. Suitable compression springs 30 encircling each stud 17, and engaging respective yokes 18 and the bearing 16, serve to force the roll 10 toward the roll 11. The compression springs 30 provide the wringing pressure for the rolls 10 and 11.

When the cover is in its normal position, that is, when it is in position on the frame member 20 as shown in Figs. 2 and 3, bosses 31 of the cover engage respective bearing members 16 and force them downwardly into contact with bridges 32 carried by the frame 20, thereby preventing the swinging of the roll 10 about its pivots 19. The arrangement of the rolls 10 and 11, together with the pivot 19, is such that the axis of the pressure roll 10 is normally slightly above a plane 55

intersecting the axes of the pivots and the other pressure roll. Hence, consequent upon the release of the cover, as will be hereinafter described, the compression springs 30 acting against 5 the pressure roll 10 cause it to ride upon roll 11 and bear against the underside of the cover 21, to force the cover upwardly, swinging it about its pivot 22.

The cover is normally held in position on the 10 frame by a pair of latches 35, one of which is disposed adjacent either end of the wringer. These latches, as shown in Fig. 5, comprise hook-shaped members, rigidly mounted on a shaft 36 carried by suitable bearings mounted on the 15 cover. The latches are normally held in engagement with pins 37, carried by the end walls 38 of the frame 20 by a spring 39, which engages the shaft and the frame, as shown in Fig. 4. The latches may be released by the operator at 20 any time by merely pressing downwardly upon either of two knobs 40 which are slidably mounted in the cover and each of which carries a plunger 41 arranged to engage one of the latches 35, to swing it, together with the shaft 36 and 25 the other latch, against the action of the spring 39, thereby permitting the compression spring 30 to raise the cover as heretofore described.

Below the pressure rolls 10 and 11 are a pair 30 of supplemental rolls. As shown, there is a supplemental roll 50 lying beneath and coacting with the pressure roll 10, and a second supplemental roll 51 lying beneath and coacting with the pressure roll 11. These supplemental rolls are like the usual rubber wringer rolls and are carried on 35 shafts 52 and 53, the ends of which are journaled in common bearing members 54, which are slidably mounted for vertical movement in guides 55 formed in the bridge members 32, heretofore mentioned.

40. The two supplemental rolls are normally urged upwardly toward and into contact with their respective pressure rolls by a pair of light compression springs 56, which are positioned between respective bearing members 54 and the 45 bottom surface of the frame. As heretofore mentioned, the springs 56 are considerably lighter than the springs 30, and the pressure between the supplemental rolls and their associated pressure rolls is such that no injury would result even 50 though the operator's fingers were caught between a supplemental roll and its pressure roll.

Disposed between the two supplemental rolls is a guide member which serves, as shown in Fig. 2, to strip the material from the supplemental roll to guide it upwardly into the bite of the two pressure rolls, thereby preventing the material from passing downwardly between the two supplemental rolls. The guide 66 extends transverse of the wringer substantially the full 60 length of the supplemental rolls, and its ends are mounted in the bearing members 54, heretofore described.

The construction above described permits clothes to be fed to the wringer from either of 65 two opposite vertical faces thereof into the bite of a supplemental roll and its coacting pressure roll, which rolls act to feed the material toward the center of the wringer where the guide member 66 diverts the material upwardly into the bite 70 of the two coacting pressure rolls, which then act to squeeze the water from the clothes and eject them from the top of the wringer.

The pressure rolls are driven by a suitable motor (not shown) but of the usual type and 75 which is connected to a vertical power shaft 65

in the usual manner. Adjacent its upper end, the shaft 65 is mounted in a suitable bearing 66 carried by a gear housing 67, to which the wringer frame 20 is secured. Upon the upper end of the shaft 65 I provide a bevel gear 68, arranged to normally mesh with the bevel gear 69 carried by a transverse shaft journaled in suitable bearings, as will hereinafter be more fully described, but which are carried by the casing 67. The innermost end of the shaft 70 extends into the 10 wringer frame 20 and is there provided with a spur gear 71, arranged to constantly mesh with a gear 72 secured to the end of the shaft 13 which supports the wringer roll 11.

The pressure roll 10 is driven by frictional contact with the roll 11. Two auxiliary rolls are geared together by suitable spur gears 75 and 76 secured to respective shafts 50 and 51. Hence, as the supplemental roll assembly is arranged to rock in the guides 55 a driving connection always exists to both auxiliary rolls because of the frictional contact between one of the pressure rolls and its coacting roll, depending upon which pressure roll is in contact with its associated supplemental roll.

25. The transverse power shaft 70 is so mounted that it may be moved to disengage the bevel gear 69 from the driving gear 68 consequent upon an abnormal separation between either supplemental roll and its associated pressure roll. As shown in the drawings, and especially Figs. 1, 4 and 6, the shaft 70 is journaled at its opposite ends in bearings 81 and 82, which are pivotally carried by suitable horizontally extending pins 83 and 84. The pins 84 carry the bearing 82 and 35 are mounted in a plate 85 which is secured to a gear housing 67 in any suitable manner. The pins 83 carry the bearing member 81 and are mounted in a slide 90 which is slidably supported for vertical movement in suitable ways 91, 40 formed in the end plate 92 of the gear housing 67.

50. The shaft 70 is constrained against axial movement relative to the bearing 82 by the gear 71 and a collar 93, which are rigidly secured to the 45 shaft at opposite sides of such bearing. The shaft is, however, free to slide axially in the bearing 81. As both bearings are pivotally mounted the shaft may be rocked about the axis of the pivot pins 82 consequent upon the raising 55 or lowering of the slide 90. The arrangement is such that the shaft 70 may be rocked to carry the gear 69 into or out of engagement with the power driven gear 68, thereby breaking the power connection to the rolls of the wringer.

55. The shaft 70 is retained in its normal operating position, shown in Fig. 4, with the gears 68 and 69 in mesh with each other by a suitable latch 95. This latch is pivoted as at 96 to the gear housing, and is normally retained in engagement 60 with a shoulder 97 formed in the slide 90 by a spring 94. A suitable compression spring 98 is carried in a recess in the end member 92 of the gear housing, and acts to constantly urge the slide 90 into its uppermost position. Hence, 65 when the latch 95 is released, that is, when the latch is disengaged from the slide, the spring 98 will rock the shaft 70 about the axis of the pivot pins 84, disengaging the wringer driving gear 69 from the power driven gear 68.

70. The latch 95 is automatically released consequent upon an undue or predetermined amount of separation between either supplemental roll and its associated pressure roll. As shown in Figs. 1, 4 and 5 the bearing members 54 which 75

support the supplemental rolls 50 and 51 are provided with outwardly extending lugs 100. These lugs are arranged to coact with respective levers 101 consequent upon a predetermined amount of separation between a supplemental roll and its associated pressure roll. The levers 101 are rigidly carried by a rock shaft 102 journalled in the bracket member 32 of the frame 20, and are provided with extensions 103 which are normally retained in engagement with the front wall 104 of the frame 20 by a suitable spring 105 (Figs. 4 and 5).

Consequent upon an undue downward movement of the auxiliary roll mounting, due to an abnormal separation between either auxiliary roll and its associated pressure roll, one of the lugs 100 will contact with its lever 101 and rock it, together with the shaft 102, in a clockwise direction (Fig. 5) whereupon the lever 101 at the 20 left-hand side of the wringer (Fig. 4) will engage one arm of a bell-crank 110 which is pivoted as at 111 to the frame 20, rocking such bell-crank in a clockwise direction. The other arm 112 of the bell-crank 110 is pivotally connected by a link 113 to the latch 95. Hence, the rocking of the bell-crank will cause the latch to be withdrawn from engagement with the shoulder 97 of the slide, thereby permitting the shaft 70 to rock, under the influence of the spring 98, to 30 disengage the gear 69 from the gear 68.

When it is desired to establish the power connection between the power shaft 65 and the wringer rolls, the operator merely depresses a plunger 115 which is slidably mounted in the gear housing 67 and which is attached to the slide 90. The depression of the slide positions it, so that it will be reengaged by the latch 95 and retained in such position until the latch is again released.

40 In Figs. 7 to 9, inclusive, I illustrate a modified form of my invention having a power shaft 70a corresponding to the shaft 70, heretofore described, but which is at all times constrained from a pivotal or swinging movement by its bearings 120. The shaft 70a is driven from the vertical driving shaft by bevel gearing in the usual manner. In the modification I utilize a clutch member 126 which is interposed between the driving shaft 70a and the gear 71a, so that the driving 45 connection between the shaft and the gear may be broken at will.

As shown in Fig. 9, the gear 71a is rotatably journalled on the shaft 70a and is arranged to be 50 drivably connected thereto by a clutch member 126. This clutch is slidably mounted on the shaft, and is drivably connected thereto by a suitable key 127. The clutch is normally maintained in engagement with a clutch face 128 formed on the hub of the gear 71a by a suitable compression 55 spring 128, which is interposed between the clutch member 126 and a collar 129, the collar being secured to the shaft 70a by a suitable nut 130. The clutch member 126 is provided with an annular flange 131, by means of which it may be moved 60 toward the right (Fig. 9), against the action of the compression spring 128, to disengage the clutch from the gear 71a and thereby sever the driving connection between the shaft and the wringer mechanism.

70 The clutch member 126 is moved out of engagement with its gear 71a by an abnormal movement of either auxiliary roll away from its coacting pressure roll. As heretofore described, an excessive downward movement of either auxiliary 75 roll causes one of a pair of lugs 100, carried by the

roll mounting, to engage suitable levers 101 carried by the rock shaft 102. As shown in Figs. 7 and 8 I provide a yoke member 135 with a pair of lugs 136 arranged to engage the flange 131 of the clutch member. The yoke member 135 has 5 an outwardly extending arm portion 138 which is normally disposed beneath the left-hand rock arm 101, so that consequent upon the depression of the rock arm, due to the abnormal separation between an auxiliary roll and its coacting pressure roll, the yoke will be rocked about its pivot 140, causing the clutch member 125 to be disengaged from the gear 71a, thereby severing the driving connection between the power rolls 71a and the driving shaft 70a and stopping the rotation of the rolls 10 and 11.

It should be noted that when using my modified form of roll drive, the pressure rolls are automatically reconnected in driving relation with the driving motor when the material causing the abnormal separation between an auxiliary roll and its coacting pressure roll is removed therefrom. This automatic reconnection is attained because the removal of such material permits the auxiliary roll to rise, which movement in turn permits the arm 101 to rock upwardly, due to the action of the spring 105. The arm 101 thus disengages from the arm 138 of the yoke 135 permitting the spring 128 to drivably reconnect the clutch 126 and the gear 71a.

With either form of my invention, the power connection between the wringer rolls and the power driving connection may also be broken at the will of the operator. As heretofore described, the operator, by depressing either of the manually operable knobs 40, causes the cover 20 to swing upwardly, under the influence of the springs 30 from the position shown in full lines in Fig. 5 to the position shown in broken lines in the same figure. This causes the wringer roll gear 72 to 40 be swung upwardly out of engagement with the wringer driving gear 71, heretofore described, thereby breaking the power connection to the rolls of the wringer.

From the foregoing description, it is obvious 45 that I have provided a wringer wherein the power driving connection to the wringer rolls may be interrupted, automatically, and I have accomplished this by providing a supplemental roll, arranged to coact with one of the pressure rolls 50 to feed material into the bite of the two pressure rolls, and also so arranged that an undue separation between such supplemental roll and its coacting pressure roll will either rock a power shaft, carrying a wringer driving gear mounted thereon, out of mesh with a gear carried by the power driven shaft, or disengage a suitable clutch mechanism interposed between the driving mechanism 55 and the wringer rolls.

I claim:

1. In a wringer, a pair of pressure rolls, a power operable driving mechanism, a separable driving connection between said mechanism and one of said pressure rolls, movable means cooperating 65 with one of the pressure rolls to guide material into the bite of the two pressure rolls, and means to separate said driving connection consequent upon the passing of a predetermined thickness of material between the guiding means and the 70 coacting pressure roll and means to automatically reestablish said driving connection consequent upon the removal of such predetermined thickness of clothes.
2. In a wringer, a pair of pressure rolls mount- 75

- ed in substantially the same horizontal plane and arranged to squeeze material fed therebetween, a power operable mechanism, a clutch mechanism interposed between said mechanism and said rolls
- 5 to selectively rotate the rolls, releasable means to maintain said clutch mechanism in position to drive said rolls, a supplemental roll, means to resiliently move said supplemental roll toward one of said pressure rolls, and means acting consequent upon a predetermined separation between said supplemental roll and the coacting pressure roll to release said releasable means and stop the rotation of a pressure roll without effecting a substantial separation of said pressure rolls.
- 10 15. 3. In a wringer, a pair of pressure rolls mounted in substantially the same horizontal plane and arranged to squeeze material fed therebetween, power operable mechanism to rotate said rolls and including a clutch, releasable means to maintain said clutch mechanism in position to drive said rolls, a pair of supplemental rolls, means to resiliently move said supplemental rolls into contact with respective pressure rolls, and means acting consequent upon a predetermined separation between either of said supplemental rolls and its coacting pressure roll at any point therebetween to release said releasable means, and means to move the clutch to disengage the wringer rolls from the power operable mechanism consequent upon such release.
- 20 25. 4. In a wringer, the combination of a pair of pressure rolls, means to guide material into the bite of the pressure rolls, including a member normally in contact with one of said rolls and movable away from such roll, power mechanism to drive said rolls, including a clutch, means normally acting upon feeding an excess thickness of material to said guide means to disengage said clutch, and means to automatically reengage said clutch upon removal of said material from the wringer.
- 30 35. 5. In a wringer, a pair of pressure rolls, a separable power driving connection to rotate said rolls, means coacting with one of said pressure rolls whereby material fed between such pressure roll and said means will be fed into the bite of the two pressure rolls, and second means whereby the passing of a predetermined thickness of material between said first-named means and its coacting pressure roll will separate said driving connection and means acting automatically on removal of such material to reestablish said driving connection.
- 40 45. 6. In a wringer, a frame, a pair of pressure rolls mounted in the frame in substantially the same horizontal plane, power operable means to rotate said rolls, including a separable positive driving connection to one roll, whereby when said connection is separated both rolls will cease rotation, means carried by the frame and arranged to grip materials fed from either of two opposite vertical faces of the frame and guide such material into the bite of the pressure rolls, said pressure rolls being adapted to coact to squeeze the materials fed from either face of the wringer without reversing the direction of rotation of said rolls, and means whereby the feeding of a predetermined thickness of material from either face of the wringer will separate the driving connection whereby the power operated mechanism will be disconnected from both pressure rolls and means acting upon removal of said predetermined thickness of material to reestablish said driving connection.
- 50 55. 7. In a wringer, a frame, a pair of pressure rolls mounted therein, yielding means to hold said rolls in wringing relation to each other, a power mechanism to drive one of said pressure rolls, and means operative on said mechanism to automatically stop the rotation of said roll consequent upon the feeding of material over a predetermined thickness to the wringer, together with means operative on said mechanism to automatically re-establish the rotation of said roll consequent upon the removal of such material from the wringer.
- 60 65. 8. In a power driven wringer, a frame, a pair of pressure rolls mounted in the frame, a guide means to direct clothes into the bite of the pressure rolls, means to stop the rotation of said rolls consequent upon feeding a thickness of clothes exceeding a predetermined thickness, between said guide means and its coacting pressure roll, and means to automatically restore said roll rotation upon removal of said excess thickness of clothes.
- 70 75. 9. In a power driven wringer, a frame, a pair of pressure rolls mounted in the frame, means to stop the rotation of said rolls consequent upon feeding of an amount of clothes in excess of a predetermined thickness to said wringer, and means to automatically restore said roll rotation upon removal of said excess thickness of clothes.
- 80 85. 10. In a wringer, a pair of pressure rolls arranged to squeeze liquid from material fed therebetween, a power operable mechanism to rotate said rolls, said mechanism including a pivoted shaft, a power operable gear, a gear on said pivoted shaft arranged to be swung into and out of engagement with said first-named gear consequent on the rocking of said shaft about its pivot, and means dependent upon the thickness of objects fed to said wringer to control the swinging movements of said shaft.
- 90 95. 11. In a wringer, a pair of pressure rolls, a gear secured to one of said rolls, a second gear arranged to normally mesh with the first-named gear, a shaft to support the last-named gear, a pivotal support for such shaft, a third gear carried by such shaft and a power operable gear arranged to mesh with said third-named gear and means automatically actuated on feeding an excess thickness of clothes to said wringer to rock said shaft, about its pivot and move a pair of said gears out of engagement with each other.
- 100 105. 12. In a wringer, the combination of a pair of pressure rolls, means to guide material into the bite of the pressure rolls, including a member arranged to coact with one of said rolls to grip and feed material therebetween into the bite of said pressure rolls, a power operable shaft, a pivoted shaft, a driving connection between said pivoted shaft and one of said pressure rolls, a driving connection between the two shafts, one of said driving connections adapted to be severed consequent upon the swinging of the pivoted shaft about its pivot, and means operable by said feeding means to control the swinging of said shaft.
- 110 115. 13. In a wringer, a pair of pressure rolls, a gear secured to one of said rolls, a second gear arranged to normally mesh with the first-named gear, a shaft to support the last-named gear, a pivotal support for said shaft, a bevelled pinion carried by the shaft and a driving pinion arranged to mesh with the bevelled pinion, and means controlled by the thickness of clothes fed to the wringer to rock said shaft about its pivot to disengage the bevelled pinion from the driving pinion.
- 120 125. 14. In a wringer, a pair of pressure rolls, a

- gear secured to one of said rolls, a second gear arranged to normally mesh with the first-named gear, a shaft to support the last-named gear, a bevelled pinion carried by such shaft and a driving pinion, means normally acting to move said bevelled pinion out of engagement with the driving pinion, a latch normally restraining said means, and second means operable consequent upon the feeding of material having a predetermined thickness into the wringer to release said latch.
15. In a wringer, a frame, a pair of pressure rolls mounted in said frame with an upwardly extending bite, means to feed clothes to the bite of the pressure rolls from either side of the wringer, power operated means to drive the pressure rolls and means operable from either side of the wringer to stop the wringing action of the pressure rolls without shifting the pressure rolls, upon feeding a predetermined thickness of clothes between the feed means and the pressure rolls.
20. In a wringer, a frame, a pair of pressure rolls carried in said frame, a pair of auxiliary rolls beneath respective pressure rolls and adapted to provide an intake bite on each side of the wringer between a respective pressure roll and auxiliary roll to guide clothes to the bite of the pressure rolls, power operated means to drive the pressure rolls and means operable upon a predetermined separation between a pressure roll and a respective auxiliary roll to stop the wringing action of the pressure rolls without substantially shifting the same with respect to each other.
25. In a wringer, a housing, a pair of pressure rolls carried in said housing, a power shaft entering said housing, a shiftable stub shaft carried by said housing and operatively connecting the power shaft and the wringer rolls, and means to stop the rotation of said pressure rolls by shifting said stub shaft to a position out of axial alignment with its previous position.
30. In a wringer, a housing, a pair of pressure rolls carried in said housing, a power shaft entering said housing, a shiftable stub shaft operatively connecting said power shaft and said pressure rolls, and means acting automatically when a predetermined thickness of clothes is fed to the wringer to shift said stub shaft and stop the operation of said rolls.
35. In a wringer, a housing, a pair of pressure rolls carried in said housing, a power shaft entering said housing, a stub shaft shiftably carried in said housing, a gear train connecting the power shaft, the stub shaft and the pressure rolls in operative relation, and means operative upon feeding a predetermined thickness of clothes to the wringer to shift said stub shaft, one of said gears carried by the stub shaft whereby shifting of the stub shaft disengages the gear from engagement with the mating gear and stops the rotation of the rolls.
40. In a multiple roll clothes wringer to which clothes may be fed from either side without bodily shifting said rolls, a pair of rolls mounted in said frame to establish therebetween a wringing pressure bite, a feeding roll and means for urging said feeding roll and one of said pressure rolls toward each other to provide a clothes intake bite, power operated means to drive the wringer, and means operable consequent upon feeding an excess thickness of material between said feeding roll and its coacting pressure roll to terminate the wringing action of said pressure rolls independently of the relative position of said pressure rolls with respect to each other.

CHARLES W. WILLIAMS.
